Primary Examiner — Cathron Brooks*Assistant Examiner* — Cary M Robinson(74) *Attorney, Agent, or Firm* — Cantor Colburn LLP(57) **CLAIM**

I claim, the ornamental design for a display screen or portion thereof with icon, as shown and described.

DESCRIPTION

FIGURE is a front view of a display screen or portion thereof with icon, showing my new design.

The broken lines in the figures illustrate the display screen or portion thereof, and form no part of the claimed design.

1 Claim, 1 Drawing Sheet(56)
